UNITED STATES PATENT OFFICE.

GEORGE L. BILBREY, OF HERMITAGE SPRINGS, TENNESSEE.

POULTRY COOP.

Application filed April 5, 1921. Serial No. 453,727.

To all whom it may concern:

Be it known that I, GEORGE L. BILBREY, a citizen of the United States, residing at Hermitage Springs, Clay County, State of Tennessee, have invented a new and useful Improvement in Poultry Coops, of which the following is a specification.

This invention relates to certain new and useful improvements in collapsible or folding poultry coops.

One of the purposes of the invention is to provide a collapsible coop of simple design capable of being easily and conveniently erected to provide a housing for the poultry or the like, or collapsed to effect a structure having such dimensions as will expedite its handling and transportation.

Another purpose of the invention is to provide a novel construction and arrangement of parts whereby, in the collapsed condition of the coop, the top and bottom members thereof may be directly secured together with the side and end members folded therebetween.

The foregoing and other purposes of the invention will be more readily understood from the following description and drawings, in which—

Figure 1 is a perspective view of a coop constructed in accordance with my invention.

Fig. 2 is an end view of the coop, as it will appear when collapsed.

Fig. 3 is a detail of the releasable connection between the top and side members of the coop, and

Fig. 4 is a detail view showing a modification of the construction illustrated in Fig. 3.

Referring more particularly to the drawings, 11 designates the bottom member of the coop and 12 the top member thereof. In the present instance, the bottom member 11 is composed entirely of wood to provide the flooring of the coop, while the top member 12 is in the form of an open rectangular wire frame. The end members of the top frame are connected and braced by a pair of comparatively heavy longitudinal wires 13, while the side members of the frame, together with the longitudinal wires 13 are connected and braced by a plurality of suitably spaced transverse wires 14. The longitudinal wires 13 are further connected and braced by a pair of spaced transverse wires 15 defining between them a door opening closed by a suitable door 16 hinged to one

of said wires 15. The said side or longitudinal members of the top frame are each formed with a plurality of offset portions forming outwardly directed U-shaped extensions 17 having the outer ends thereof directed downwardly to provide stops 18 and adapted to be utilized as hereinafter explained.

The side members of the coop are carried by the bottom member 11 and each comprises an open rectangular frame having the lower longitudinal member 19 thereof hinged to the bottom member 11 by means of the straps 20 and the upper longitudinal member 21 thereof provided with inwardly directed offset portions 22 providing depressions 23 in which the U-shaped extensions 17 of the top member frame are fitted, as shown to advantage in Figs. 1 and 3. The longitudinal members 19 and 21 of this frame are connected by transverse wire 21'.

The end members of the coop are carried by the top member 12 and each comprises an open rectangular frame having the upper longitudinal member 24 thereof hinged to an end of the top member frame as indicated at 25 and the lower longitudinal member 26 thereof provided with a plurality of inwardly directed offsets forming horizontally disposed loops 27 engageable with hooks 28 projecting upwardly from the bottom 11. A depressible spring carried by the bottom member 11 at each end thereof is adapted to bear against the lower horizontal member 26 of each end frame to hold the loops 27 of said member in engagement with the hooks 28. Transverse wires 28' extend between the longitudinal members 24 and 26.

From the foregoing, it will be seen that in the set up position of the coop shown in Fig. 1, the upper edges of the side members of the coop are received between the sides of the top member 12 and the stops 18 carried by the members 17, while the lower edges of the end members have the loops 27 thereof held in engagement with the hooks 28 by means of the springs 29.

When it is desired to collapse the frame, the springs 29 are depressed to permit the end members to swing upwardly against the under side of the top member 12, and when this has been done, the side members of the coop may be disengaged with the projections 17 and swung downwardly to lie upon the upper side of the bottom member 11.

When the side and end members have been

folded in the manner described, the top member 12 and bottom member 11 may be placed together as shown in Fig. 2 with the side and end members folded therebetween.

5 In order to secure the top and bottom members together in the folded position shown in Fig. 2, the top member 12 has a pair of catch members 30 pivoted to each of the rods 13 and located adjacent opposite ends of 10 said rods. Each member 30 comprises a U-shaped piece of wire having the arms thereof coiled about the wire 13 as indicated at 31 and then curved to form hooks 32 engageable with suitable staples 33 carried by 15 the bottom member 11. Thus, when the top and bottom members are assembled as shown in Fig. 2, each catch member 30 may be swung on the rod 13 to engage the hooks 32 thereof beneath a pair of staples 33, thus 20 holding the top and bottom members against separation and retaining the end and side members in folded position therebetween.

In order to limit the outward swinging movement of the sides of the coop relative 25 to the bottom member 11 when setting up the coop a plurality of hooks 34 are provided, each hook having one end pivoted to the bottom member 11, and the opposite end curved to engage over one of the transverse wires 21 of the side members.

In the modification shown in Fig. 4, the ends of the offset 22 defining the depression 23 are inclined as shown to provide shoulders 23' at the mouth of the offset 35 and in this instance, it is necessary to spring the extension 17 beyond said shoulders when inserting the member in the depression, the shoulders subsequently holding the member against accidental displacement.

From the foregoing, it will be evident that I have provided a coop which is capable of being readily set up to provide a housing for the poultry or the like, or 45 readily collapsed when it is desired to reduce the dimensions of the coop, as in shipping the same from place to place. I do not, however, wish to be confined to the exact details of construction and arrangement set forth herein, but reserve the right to resort to such modifications as may be desired and come within the spirit and 50 scope of the appended claims.

What is claimed is:

55 1. A collapsible coop comprising separable top and bottom members, projections extending outwardly from each side of said top member and provided at their outer ends with depending stops; side pieces 60 hinged to each side of the bottom member, each of said members having a plurality of depressions formed in its free longitudinal edge adapted to accommodate the projections of the top in the set up position 65 of the coop, end members hinged to said

top member, and means for releasably connecting the end members to the bottom member.

2. A collapsible coop comprising a bottom member, side pieces hinged to said bottom member and swingable to folded position against the upper side of the member, a top member, end pieces hinged to the ends of said top member and swingable to folded position against the underside of 70 the top member, means for releasably connecting the side pieces to the top member and the end pieces to the bottom member in the set up position of the crate, and means for releasably connecting the top and 75 bottom members together with the side and end members folded therebetween.

3. A poultry coop comprising top and bottom members, side walls connected between said members in foldable relation 80 therewith, end walls hinged to one of said members, retaining elements carried by the other member for releasable engagement with said end walls, and springs arranged to hold said end walls engaged with said 85 retaining members.

4. A poultry coop according to claim 3, wherein the said springs are depressible to permit disengagement of the end walls and 90 retaining means.

5. A poultry coop comprising a bottom member, a top member comprising a rectangular wire frame having each of two opposite sides offset near its extremities to provide a pair of U shaped loops projecting 100 outwardly in the plane of the top member and provided with depending extremities and side members hinged at their lower edges to the bottom member and recessed at their upper edges for the reception of said 105 U shaped loops, the depending projections of the loops being adapted to lie outwardly of the side members to restrain the latter against outward swinging movement.

6. A poultry coop according to claim 5, 110 in which the loops of the top member are held in compression between opposing walls of the recesses provided therefor in the side members.

7. A poultry coop comprising top and 115 bottom members, end members hinged at their upper longitudinal edges to the top member and offset at their lower edges to provide horizontally disposed loops opening outwardly, retaining elements projecting upwardly from the bottom member adapted to be embraced by said loops to hold the end members against outward swinging movement, means engaging the end members to releasably hold them 120 against inward swinging movement with respect to said retaining members and side members connected between said top and 125 bottom members.

G. L. BILBREY.
